UNITED STATES PATENT OFFICE.

BENJAMIN PORTER, OF ELLENDALE, NORTH DAKOTA, ASSIGNOR OF ONE-HALF TO FRED L. WALKER, OF SAME PLACE.

LAP-ROBE HOLDER.

SPECIFICATION forming part of Letters Patent No. 552,198, dated December 31, 1895.

Application filed February 12, 1895. Serial No. 538,090. (No model.)

To all whom it may concern:

Be it known that I, BENJAMIN PORTER, a citizen of the United States, residing at Ellendale, Dickey county, North Dakota, have invented certain new and useful Improvements in Lap-Robe Holders, of which the following specification contains a full, complete, and exact description, reference being had to the accompanying drawings, in which—

10 Figure 1 represents my invention as in use. Fig. 2 is an enlarged perspective of the holder detached. Fig. 3 is a fragmentary view mainly showing the friction-slide in full and dotted lines. Figs. 4 and 5 are details of the same. Figs. 6 and 7 are details of the clasp-slide, and Fig. 8 is a partly-longitudinal section of one of the clasps and a portion of the back-strap.

15 The object of the invention is to provide a lap-robe holder separate and independent of the robe and vehicle, and which may be passed around the back of the person and be secured by means of clasps adjustably connected to its ends to the lap-robe so as to hold the robe close around the person and permit free movement without strain on the holder.

20 The invention will first be described and then specifically pointed out in the claims.

A represents the back-band formed preferably of a stout piece of webbing, to the ends of which are adjustably connected the two clasps B B'. These clasps each comprise a member b terminating at its outer end in an inwardly-curved serrated jaw b', and near the opposite end of the said member b on its inner side are formed parallel ears b², between which is pivoted the rear end of the swinging member b³ of the clasp, the forward end of the member b³ terminating in a serrated jaw b⁴, which is opposed to the jaw b' of the member b. The two members b b³ are forced toward and from each other by means of a slide C which has two slots c c, through which pass the body portions of said members, the outer cross-bars c' c² of the slide serving to force the jaws together when the slide is moved outwardly, and the middle cross-bar c³, which engages the adjacent faces of said members, forces them positively apart as the slide is moved rearwardly. Thus the use of springs is entirely obviated.

25 The clasp B at the inner end of its member b is formed with a transverse slot or loop through which one end of the web is loosely passed, said end being folded upon itself and provided with a friction-slide D having an outer cross-bar d around which the extremity of the web is secured, while the inner end of the slide is provided with a slot d', through which the main portion of the web is free to slide when the slide is turned at right angles thereto. The upper cross-bar d² of the slot d' is provided on the outer side which comes next to the web A with a series of pointed teeth d³, which engage the outer face of the web when the slide is turned parallel with the web or at less than a right angle thereto, as shown in Fig. 3, and thus all slipping of the slide along the web is prevented.

30 In order that the slide D may be moved freely along the web in adjusting it to the person, the inner face of the cross-bar d² is beveled outwardly, as shown at d⁴.

35 The web A will be bent twice at right angles in passing through the slot d' when the slide is under tension, and this in connection with the teeth d³ will firmly hold the slide in its adjusted position.

40 The clasp B' is provided at the inner end of the main member b with two outwardly-projecting ears b⁵ which are connected at their bases by a flat cross-bar b⁶ having a groove b⁷ across its outer face. Between the ears is pivoted an L-shaped clamp E, the clamping section or jaw e of which forces the web A into the said groove and firmly holds it there, the handle-section e' of the clamp resting on the outer side of the webbing, as shown in Fig. 8.

45 The webbing A is passed under the jaw e, around the cross-bar b⁶ and thence rearwardly upon itself.

50 The clamp E forms an auxiliary adjustment and will be used in case the slide D has been moved around behind the person too far for ready access, or in the event of the robe-holder being used to hold the robe around two persons the web A may be adjusted from either or both ends, as may be desired. The strain on the web will hold the clamp E closed; but it may be readily released by swinging its handle-section outwardly.

The outer sides of the clasp members b are corrugated or grooved transversely, and the inner face of the outer cross-bars c' of the slides C are rounded so as to enter the grooves 5 and hold slides in their adjusted positions.

It will be seen that my lap-robe holder is an article wholly independent of the robe and adapted for application to any and all lap-rob- 10 es. Moreover, it is not connected to any portion of a vehicle, and therefore allows of unrestricted movement of the person.

In use the person simply passes the band around him and connects the two clasps to the robe. Then by operating the slide or the 15 clamp the proper adjustment will be effected.

What I claim as new, and desire to secure by Letters Patent, is—

1. A lap-robe holder comprising the back-band or strap A , provided at its ends with 20 clasps each consisting of two flat members b , b^3 formed at their outer ends with the wide jaws $b' b^4$ having teeth on their abutting edges, each member b having an integral loop at the inner extremity for the band A and integral 25 ears b^2 between which the inner ends of the members b^3 are pivoted, and the rectangular slide C provided with parallel transverse slots $c c'$ through which said members $b b^3$ pass; the said slots being separated by a cross piece 30 c^3 which lies between the members $b b^3$ and forces them positively apart when the slide is moved rearwardly while the outer cross-pieces $c' c^2$ of the slide engage the outer faces of the members $b b^3$ and force said members together 35 when the slide is moved outwardly, substantially as described.

2. The clasp consisting in the two flat members $b b^3$, provided at their outer ends with the wide jaws $b' b^4$, having teeth on their abut-

ting edges; the rear ends of the member b 40 being formed with integral ears b^5 connected by a flat cross-piece b^6 spaced away from the end of said member to permit a strap or band to be passed around the inner edge of the said cross-piece and back over its inner face, a 45 lever clamp E pivoted between the said ears with its jaw e projecting toward the inner face of the cross piece and its free or operating arm e' projecting rearwardly away from the clasp, the member b^3 being pivoted between the ears 50 in front of the said cross-piece, and the rectangular slide having transverse parallel slots receiving the members $b b^3$ said slide serving to positively open and close the jaws, substantially as set forth.

3. As an improved article of manufacture, a lap-robe holder comprising the back-band A , the two clasps $B B'$, each formed of two flat members $b b^3$ pivoted together at their rear ends and having wide toothed jaws $b' b^4$ 60 at the outer ends, the member b of the clasp B having an integral loop through which passes one end of the strap, a slide D having the slot d' through which the band slides and the cross bar d to which its extremity is secured, the ears b^5 integral with rear end of member b of clasp B' , the flat cross piece b^6 connecting said ears and spaced from end of the members $b b^3$, the lever clamp E , engaging with its jaw e the end of the band passing 65 around and over said cross piece, and the two slides C upon the clasps for positively opening and closing their members, substantially as set forth.
